(57) **CLAIM**

(22) Filed: **May 18, 2001**

The ornamental design for a connector for printed circuit boards, as shown and described.

(30) **Foreign Application Priority Data**

DESCRIPTION

Nov. 30, 2000 (JP) 12-034201

FIG. 1 is a top plan view;

(51) **LOC (7) Cl. 13-03**

FIG. 2 is a front elevation;

(52) **U.S. Cl. D13/147**

FIG. 3 is a bottom plan view;

(58) **Field of Search** D13/146, 147;
439/247, 378, 680, 74, 79, 83, 62

FIG. 4 is a right-side elevation;

(56) **References Cited**

FIG. 5 is a rear elevation; and,

FIG. 6 is a perspective view of the connector, wherein the left-side elevation thereof symmetrical with the right-side elevation is not included.

The present design is characterized in that the connector has a forward portion generally of a reversed-T shape in cross section and a rectangular rear portion that has eyes and formed integral with the forward portion, wherein one of the contacts extends along the top and the other contacts along the bottom of the insulated housing of the connector.
